UNITED STATES PATENT OFFICE.

WALTER E. SMILY AND THOMAS HANNAH, OF PITTSBURGH, PENNSYLVANIA, AND
MILTON E. WINANS, OF IRVINGTON, NEW JERSEY; SAID HANNAH AND WINANS
ASSIGNORS TO SAID SMILY.

CALENDAR BANK.

Application filed October 29, 1926. Serial No. 144,972.

This invention relates in general to improvements in banks and more particularly to savings banks of the type containing a perpetual calendar, which, is advanced daily by the insertion of appropriate coins, thereby encouraging systematic and regular saving.

Objects of the invention are the providing of such a bank with a minimum number of operating parts, simple in construction and operation, capable of being manufactured at extremely low cost in order to encourage their distribution by institutions; the providing in such a bank for the advancement of the calendar elements by the direct engagement of the coin itself with the elements; the arrangement of mechanism in such a bank so that the inserted coin itself holds the calendar elements against more than a one-step movement upon or after the insertion of a coin and positively prevents overthrow or flirting of the calendar elements; the provision in such a bank of means for holding an inserted coin in restraining engagement with the calendar elements until it is ejected by the insertion of another coin, such means also acting as a pawl to prevent backward rotation of the calendar elements; the provision in a bank, constituted as above specified, of means for indicating the month, day and date respectively, each of such means being operable independently of the others; and the invention has for further objects such other improvements or advantages in construction, operation or results as are found to obtain in the apparatus hereinafter described or claimed.

In the accompanying drawings forming a part of this specification and showing, for purposes of exemplification, a preferred form and manner in which the invention may be embodied and practiced, but without limiting the claimed invention specifically to such illustrative instance or instances:

Figure 1 is a front elevational view of a calendar bank embodying our invention; Fig. 2 is a top plan view of the same; Fig. 3 is a vertical sectional view through the casing of the bank; Fig. 4 is a vertical cross-sectional view taken on the line 4-4 of Fig. 3; and Fig. 5 is a horizontal view taken on the plane of the line 5-5 of Fig. 3.

In its present embodiment, the invention is incorporated in savings banks, such as calendar banks. For convenience, the present description will be confined to this use of the invention. Features of the invention are, however readily susceptible of other valuable application; consequently, the scope of the invention is not confined to the specific use and specific embodiment herein described as an illustrative example.

The calendar bank embodies in its construction a casing 10 having a bottom 11 and a top 12. The front of the casing 10 is provided with three sight openings, 13 for legends indicating the month of the year, 14 for legends indicating the day of the week, and 15 for legends indicating the day of the month. The rear of the casing is provided with a hinged door 16 which may be opened to remove the accumulated coins, said door being provided with a lock.

Three registering wheels or independent calendar disks 18, 19 and 20, for months, day of the week and day of the month respectively, are mounted to rotate on a common shaft 21, which is secured to the sides of the casing 10. The disks 18, 19 and 20, having their proper indicia inscribed on their periphery 22, are mounted on the shaft 21 and spaced from each other so that the indicia on their peripheries may be brought into close proximity to their respective sight openings as is best seen in Fig. 4. Each of the calendar disks 18, 19 and 20 is provided with series of teeth 23 on their peripheries, the teeth providing spaces 24 through which the coins may pass. Each tooth is beveled at 25 so that as a coin rides over such beveled surface it advances the calendar disk one step before the coin fully enters space 24 between such tooth and the next tooth.

The disk 18 may be provided with sufficient teeth to accommodate one or more series of twelve months, likewise the disk 19 may be provided with sufficient teeth to accommodate one or more series of days in a week and the disk 20 similarly may be provided with teeth to accommodate one or more series of days in a month. Preferably each disk has sufficient teeth to accommodate a plurality of series of teeth for their respective indicia.

In the casing top three coin slots 26 are provided, one for each of the disks 18, 19

and 20. Each slot is arranged in the casing top so as to be substantially parallel with the angularly arranged sides 27 of the teeth 24. Mounted in each coin slot is a spring 28 secured to the top of the casing at 29. Each spring has a depending portion 30 bent at 31 to provide a forwardly extending pawl 32 which rides over the teeth of its respective disk and acts to prevent backward rotation 10 of its disk. The rearwardly extending portion 33 operates to hold the lower portion 34 of an inserted coin in the space 25 between the teeth immediately below the coin slot, so as to engage the teeth of the disk while 15 the upper portion of that coin remains between the spring and a depending bracing member 17 at one side of the slot until a next coin that is inserted forces the holding coin downwardly until the upper portion 35 20 is clear of the coin slot, at which time the previously inserted coin drops into the lower portion of the bank and the inserted coin engages the beveled surface 25 and advances the disk one step before it fully enters the 25 next space 24 between the teeth to restrain further movement of the registering wheel or calendar disk.

From the foregoing description it will be apparent that the spring will hold the lower 30 portion of a coin in engagement with the disk while the upper portion remains between the spring and one side wall of the slot, consequently the coin itself will hold the disk after it has advanced the disk only 35 one step, and cannot be released but must remain in restraining engagement with its disk until the portion of the holding coin is released from engagement with the side of the coin slot by the insertion of another 40 coin.

The invention as hereinabove set forth is embodied in particular form but may be variously embodied within the scope of the claims hereinafter made.

45 We claim:

1. A calendar bank comprising, in combination: a casing having a plurality of coin slots therein; a separate registering wheel for each slot, each of said registering wheels 50 being mounted within said casing for ad-

vancement by direct engagement with an inserted coin, each of said registering wheels having a series of teeth thereon; a spring mounted adjacent each coin slot and its respective series of teeth, each of said springs 55 being adapted to hold an inserted coin in its slot so that one portion thereof is in restraining engagement with the teeth of its respective registering wheel while another portion of said coin is within the confines of its slot 60 until another coin is inserted in said slot, and each of said springs also engaging the teeth of its respective registering wheel to prevent backward rotation of its registering wheel, substantially as specified. 65

2. A calendar bank comprising, in combination: a casing having a plurality of coin slots therein; a separate registering wheel for each slot, each of said registering wheels being mounted within said casing for advancement by direct engagement with an inserted coin, each of said registering wheels having a series of teeth thereon; a spring mounted adjacent each coin slot and its respective series of teeth, each of said springs 70 75 being adapted to hold an inserted coin in its slot, so that one portion thereof is in restraining engagement with the teeth of its respective registering while another portion of said coin is within the confines of its slot 80 until another coin is inserted in said slot, substantially as specified.

3. A calendar bank comprising, in combination: a casing; a registering wheel mounted within said casing for advancement by 85 direct engagement with an inserted coin; and means for holding such coin in direct engagement with said registering wheel to restrain further movement thereof after it has been advanced by such coin and until such 90 coin is ejected from such direct restraining engagement by the insertion of another coin, substantially as specified.

In testimony whereof we have hereunto set our hands this 29th day of September, 95 1926.

WALTER E. SMILY.
THOMAS HANNAH.
MILTON E. WINANS.
